(57) CLAIM

The ornamental design for a sports bra, as shown and described.

DESCRIPTION

FIG. 1 is a front view of a sports bra, showing my new design;

FIG. 2 is a rear view thereof;

FIG. 3 is left side view thereof;

FIG. 4 is a right side view thereof;

FIG. 5 is a top view thereof; and,

FIG. 6 is a bottom view thereof.

The broken lines in the drawings showing stitching depict portions of the sports bra that forms no part of the claimed design. The broken lines in FIGS. 1 and 2 showing the human figure depict environment and form no part of the claimed design.

1 Claim, 6 Drawing Sheets
